UNITED STATES PATENT OFFICE.

LEWIS P. LITZINGER AND PETER F. CONERTY, OF BUTLER, AND WILLIAM SNODGRASS,
OF BRUIN, PENNSYLVANIA.

PROCESS AND APPARATUS FOR DISTILLING FUEL OIL OR GAS OIL.

Application filed May 2, 1921. Serial No. 465,996.

To all whom it may concern:

Be it known that we, LEWIS P. LITZINGER and PETER F. CONERTY, both of Butler, county of Butler, State of Pennsylvania, 5 citizens of the United States, and WILLIAM SNODGRASS, of Bruin, in the county of Butler and State of Pennsylvania, a citizen of the United States, have invented certain new and useful Improvements in Processes 10 and Apparatus for Distilling Fuel Oil or Gas Oil, of which the following is a specification.

This invention relates to a process and apparatus for distilling by means commonly known as cracking, under pressure in excess of atmospheric, the hydro-carbons or petroleum residues of the higher boiling points commonly termed fuel oils or gas oils.

The invention provides a process and apparatus wherein the distillation is affected by means commonly known as cracking, under pressure in excess of atmospheric, of the hydrocarbons or petroleum residues of the higher boiling points to increase the yield of the 25 lower boiling point oils, wherein the process is carried on with relative safety, facility, and with a relative high yield of the light oils. The invention further provides an apparatus of simple construction and 30 mode of operation.

It has heretofore been observed that in the process of distilling hydro-carbons or petroleum residues or fuel oils or gas oils of the higher boiling points there is a separation of carbon from the oil, and that this carbon, or settling, together with other solids or foreign matter in the oil, formed an adherent deposit on the inside bottom of the still, which deposit acted as an insulating coating on the inside bottom of the still. This coating necessitated the use of higher temperatures in the furnace in order to transmit the required amount of heat to the oil in the still, consequently necessitating additional fuel and danger due to overheating and burning of parts of the still in that portion where deposit or coating has been formed, making it necessary to draw the fires and leave in the still a 45 large portion of the charge which, by the use of this apparatus, can be taken off in volatile matter in substantially larger quantities.

It has heretofore been proposed to overcome the foregoing disadvantages by scrap-

ing the deposit from the inside walls of the still during, or after, the distillation operation.

According to the present invention the objectionable features of the distillation are avoided in a more rational way, by producing such a circulation in the still that the deposit of carbon is greatly retarded and diminished, particularly on that part of the still subjected to the greatest temperature 60 from furnace gases, and further while carrying out the process so that the deposit does not occur on the hotter parts of the still, it may be so conducted that the carbon and other solids may be conveyed to 65 and deposited, or concentrated, in another part of the still where the heat from the furnace gases is less intensive and there collected.

An embodiment of the apparatus according to the present invention is illustrated in the accompanying drawings wherein:

Figure 1 is a longitudinal sectional view of said embodiment, and Figures 2 and 3 are cross-sectional views on the lines 2—2 70 and 3—3 respectively Figure 1.

Figures 4, 5 and 6 are detail views of the blades shown in Figures 1 and 2.

The apparatus will be first described: Numeral 10 designates a still, preferably of 85 elongated cylindrical form and adapted to be used in horizontal or substantially horizontal position and heated by either coal, oil or other fuel in such manner that there is a part A subjected to hotter gases, than 90 another part, or part B thereof, subjected to gases of lesser temperature as is moreover the usual condition in furnaces of oil stills. The still may be charged through one of the man-holes (12) and the distilled vapors may 95 pass off from the still through the vapor outlet (14).

Means (20) are provided for producing a vigorous circulation in the still. The circulating means (20) is conveniently in the 100 form of a horizontal shaft (22) having blades (24) thereon, the shaft running lengthwise substantially throughout the entire length of the still, near the bottom, and well below the normal liquid level thereof, 105 as shown. The shaft is conveniently supported by hangers (26) attached to the inner walls of the still. The shaft (22) is conveniently rotated or revolved by means of a drive shaft (30) passing into the still 110

(10) through a stuffing box (32), and connected to shaft (22) by means of bevel gears (35 and 36) and said vertical shaft being guided and held plumb at its lower end by 5 guide shoulders or collars (28) on said horizontal shaft, and said vertical shaft being guided and held in vertical position by shoulders or collars (31 and 33).

The blades (24) are conveniently in the 10 form of plates of metal bent outwardly along a diagonal line, as indicated at (40), Figure 5, and the shaft is conveniently provided with flats (42) to which the blades (24) are attached (see Figure 4).

15 The blades (24) being of uniform lengths may or may not be of the same widths while those at or near the respective ends of the shaft, as indicated at 45 and 46, may preferably be of somewhat lesser widths.

20 Conveniently in the part B of the still (10) where the heat from the furnace gases is less intensive, it may be provided with a dead space (50) and the end of the shaft (22) nearest the dead space may be provided with paddles (55) adapted to churn 25 the carbon accumulation as thus conveyed to the so-called dead space and to hold it in that point in suspension in the still content. These paddles (55) may be flat and 30 perforated, as indicated at 57, see detail Figure 6. The carbon accumulation held in suspension in the dead space 50 may be drawn off at the termination of the still run through the pumping out pipe (59).

35 The speed of rotation of the shaft (22) in order to obtain the proper rapidity of circulation will depend somewhat on the character of the oil being distilled and also upon the size and form of the still, and size 40 and pitch of blades (24).

Process.—In the process known as cracking, and as ordinarily employed, there is a 45 liberation of free carbon which, together with other solids in the oil, precipitates and incrustates on the inside still bottom, particularly on the portion where the heat from the furnace gases is most intensive; and to overcome such precipitation and incrustation, this process, as shown by device 20 and 50 particularly indicated by the arrows in Figure 1, creates an increased circulation of the liquid within and beyond the zone of the circulating or propelling apparatus, thereby propelling or conveying a large portion of 55 the carbon and other solids (which otherwise would be formed and precipitated) toward the rear or dead space of the still or retort, where the heat from the furnace gases is less intensive and the ebullition or 60 agitation less active and there interrupted in its forced circulation by means of paddles 55, Figure 1, and thereby substantially diminishing the quantity of carbon deposit or other solids on the inner surface of the 65 still or retort at the point where the bulk or

content and the outer surface of the still or retort are exposed to the greatest temperature of furnace heat gases and direct flame.

Moreover the apparatus and operation as 70 described substantially increases the yield of volatile matter from a given quantity of petroleum residue or fuel oil during the process known as cracking by means of retarding and minimizing the volume of precipitation and incrustation which ordinarily 75 more rapidly forms on inside bottom of the still where the heat from the furnace gases is most intense causing a burning of the still bottom and necessitating the drawing of the fires and leaving in the still a large portion of the charge which, by means of this apparatus, can be taken off in volatile matter in substantially larger quantities.

The apparatus may receive other embodiments than that herein specifically illustrated and described and the process may be carried out in other particular modes than that specifically described.

What is claimed is—

1. A method of distilling by means commonly known as cracking, under pressure in excess of atmospheric, the hydro-carbons or petroleum residues, and particularly of the higher boiling points, commonly termed fuel oil or gas oil, comprising producing a forced circulation of the oil in the bottom of the still toward one end, whereby the maximum accumulation or collection of carbon and other solids is produced at one end and precipitation and incrustation thereof on the inside bottom of the still at other than the end portion (where the heat from the furnace gases is most intense) are retarded and minimized, and conveying the carbon and other solids to a dead space at said end of the still and there positively retarding the endwise circulation whereby they may be collected as a sediment at the termination of the still run.

2. A method of distilling by means commonly known as cracking, under pressure in excess of atmospheric, the hydrocarbons or petroleum residues, and particularly of the higher boiling points, comprising producing a forced circulation of the oil towards a cool part of the still and there agitating the oil to prevent carbon deposition at said cool part, and effecting a separation of carbon particles in the oil at said cool part.

3. In a still for oil, means for producing a forced longitudinal circulation therein whereby deposit of carbon and other solids on the inside bottom of the still is retarded and minimized, said means comprising a shaft running longitudinally of the still and said still being in the form of an elongated cylinder, having a dead space wherein suspended particles in the oil are adapted to collect, and blades on said shaft, said blades

having no pitch at a point in the dead space in said still.

4. In a still for oil, means for producing a forced longitudinal circulation therein, whereby deposit of carbon and other solids on the inside bottom of the still (where the temperature from the furnace gases is most intense) is retarded and minimized, and a dead space, in a cooler part of said still, means in said dead space for agitating the oil thereat to prevent carbon deposition and means for separating carbon particles at said dead space.

5. In a still for oil, means for producing a forced longitudinal circulation therein, whereby deposit of carbon and other solids on the inside bottom of the still (where the temperature from the furnace gases is most intense) is retarded and minimized and a dead space in a cooler part of said still wherein said carbon and solids may collect, and means for interrupting the longitudinal flow of said carbon and other solids at said dead space and thereby accumulating them, during the process of distillation, and then collecting as a sediment in the said dead space at the termination of the still run.

6. In a still for oil, means for producing a forced longitudinal circulation therein, whereby deposit of carbon and other solids on the inside bottom of the still is retarded and minimized, said means comprising a shaft running longitudinally of the still, and said still being in the form of an elongated cylinder, and blades on said shaft, a dead space in the cooler part of said still, wherein said carbon and solids may collect and paddles on said shaft for interrupting the flow of said solids at said dead space and thereby collecting the solids.

7. In a still for oil, means for producing forced longitudinal circulation therein,

whereby in the process of distilling commonly known as cracking, under pressure in excess of atmospheric, the deposit of carbon and other solids on the inside bottom of the still (where the heat from the furnace is most intense) is retarded and minimized by being conveyed to, and collected in, the rear of the still where the temperature of the furnace gases is less intense, said still being of elongated cylindrical form in substantially a horizontal position, and having a dead space at one end, said means for producing the forced circulation comprising a horizontal shaft running lengthwise substantially throughout the entire length of the still and extending to a position near the bottom and well below the normal liquid level thereof, hangers from the inside walls of the still for supporting said shaft, and blades of metal firmly attached to said shaft, certain of said blades being bent outwardly or pitched so as to propel the liquid to a point near the rear of the still, and said blades near the rear of the still being without any pitch or curve, means for rotating said horizontal shaft comprising a vertical shaft and bevel gears connecting said shafts, a stuffing box at the top of the still shell, through which said vertical shaft passes, hangers for said vertical shaft, collars on said vertical shaft bearing on said hangers and underside of the still shell, and guides provided by collars or shoulders on the horizontal shaft, for the end of said vertical shaft.

Signed at Butler, in the county of Butler and State of Pennsylvania, this 28th day of April, A. D. 1921.

LEWIS P. LITZINGER.
PETER F. CONERTY.
WILLIAM SNODGRASS.
